United States Patent Office

Des. 188,388
Patented July 12, 1960

188,388

ILLUMINATION DIFFUSER

Arnold Goldstein, 3363 Trexler Road, Allentown, Pa.

Filed Sept. 12, 1958, Ser. No. 52,633

Term of patent 14 years

(Cl. D48—16)

Fig. 1

Fig. 2

I claim:

The ornamental design for an illumination diffuser, substantially as shown.
